UNITED STATES PATENT OFFICE

SAMUEL WEBB, OF GLASSPORT, PENNSYLVANIA.

BRAKE-SHOE FASTENING.

No. 828,159.

Specification of Letters Patent.

Patented Aug. 7, 1906.

Application filed January 10, 1906. Serial No. 295,453.

To all whom it may concern:

Be it known that I, SAMUEL WEBB, a citizen of the United States of America, residing at Glassport, in the county of Allegheny and State of Pennsylvania, have invented new and useful Improvements in Brake - Shoe Fastenings, of which the following is a specification.

This invention relates to improvements in means for securing detachable brake-shoes to brake-heads, the object of the invention being to provide a simple form of fastening which will firmly and securely hold the shoe in applied position and yet will permit of its ready removal when worn and the substitution of a new shoe.

Another object of the invention is to provide a fastening adapted for use in conjunction with brake-heads and shoes of the type in common use and by which a shoe may be effectually secured to a worn brake-head, thus obviating the necessity of discarding a complete brake-beam and equipment whenever the brake-head is worn, so that a shoe cannot be applied thereto through the medium of the fastening means now in common use.

In the accompanying drawings, Figure 1 is a longitudinal section of a brake-shoe and head connected by my improved fastening. Fig. 2 is a similar view showing a modification of the fastening. Fig. 3 is a detail view of the key and clip removed.

Referring to the drawings, the numeral 1 designates a brake-shoe of ordinary construction provided with channeled upper and lower ends 2 and 3 and having terminal notches 4 and 5, and 6 designates a brake-shoe of ordinary construction provided with end projections 7 and an intermediate apertured lug 8, arranged upon the rear face thereof.

In the ordinary construction now in common use the brake-head is provided with apertured lugs to fit above and below the lug upon the shoe, and a key passes through these lugs and bears upon the projections 7 to hold the parts connected. The lugs upon the head are frequently damaged or worn away, and when this occurs the brake-beam and its entire equipment is generally discarded, as it is found in practice that in view of the amount of labor required to remove an old brake-head and apply a new one it is nearly as cheap to remove the beam carrying the damaged head and to substitute a new

beam with applied parts therefor, since the discarded beam is melted and utilized as scrap. The main object of my invention is to provide a construction of fastening which will obviate the necessity of removing a beam even in the event of the lugs upon the brake-heads being completely worn away or broken off and which will accordingly permit of a new shoe being conveniently and quickly fastened upon the damaged heads by a train-hand or other person unskilled in the use of tools, thus avoiding the expense of high-class labor and the necessity as now experienced of discarding brake-beams having worn heads. To this end I provide a key 9, longitudinally curved in the customary manner and adapted to be passed through the apertured lug 8. This key is provided with a hooked upper end 10, adapted to lie in the recess 4 and to engage the upper edge of the body portion of the brake-head, the lower end of the key being adapted to rest upon the projection 7 at the lower end of the shoe. Upon the lower end of the key is arranged a clip 11, apertured for sliding engagement with the key and provided with a lug or finger 12. After the applied key has been engaged by its hooked end 10 with the upper end of the brake-head the clip is applied to the lower end of the key and adjusted to seat within the recess 5 and to bring the lug 12 to bear against the rear surface of the lower end of the body of the brake-head. The fastening will thus be engaged with both ends of the brake-head and will firmly and securely hold the shoe thereto, the pressure of the lower end of the key on the projection 7 retaining the clip 11 in applied position. Where there is any wear upon the parts, however, under which the clip 11 is liable to become loose, the body portion of the clip may be provided with a threaded opening for the reception of a set screw 13 to bear upon the key and fix the clip in position. It will thus be seen that the construction of the fastening is such as to permit the brake-shoe being applied to and removed from a brake-head by an unskilled mechanic and in a short time without the use of tools and that it is not necessary in my improved fastening to employ lugs upon the brake-head. Hence a new shoe may be firmly and securely fastened upon a brake-head on which the lugs have been worn to such an extent as to be unfit for further use or from which the lugs have been entirely broken away.

Having thus described the invention, what is claimed as new is—

1. In combination, a brake-head, a brake-shoe provided with a lug, and a key passing through said lug and having a hooked engagement at its ends with the ends of the brake-head.
2. In a brake-shoe fastening, a brake-head, a brake-shoe, and a key centrally engaged solely with the shoe to hold the same from forward displacement and terminally connected with the ends of the head, the head and shoe being of the commercial type and free from other connections.
3. In a brake-shoe fastening, the combination of a brake-head having notched upper and lower ends, a brake-shoe provided with a central lug, and a key passing through said lug and provided with engaging members occupying said notches and gripping the ends of the brake-head.
4. In a brake-shoe fastening, the combination of a brake-head, a brake-shoe, and a key detachably connected centrally with the brake-shoe and having clips engaging the ends of the head.
5. In a brake-shoe fastening, the combination of a brake-head, a brake-shoe having a lug, a key extending through said lug and provided at one end with a hook to engage one end of the head, and an adjustable clip upon the other end of the key to engage the other end of the head.
6. In a brake-shoe fastening, the combination of a brake-head, a brake-shoe having an apertured lug, a key passing through the lug and having an integral loop at one end to engage one end of the head, and an adjustable clip upon the other end of the key having a finger to engage and bear upon the other end of the head.
7. A key for fastening brake-shoes to brake-heads provided with terminal clips to engage the ends of a brake-head.
8. A key for fastening brake-shoes to brake-heads having a hook at one end to engage one end of the head and an adjustable clip at its opposite to engage the other end of the head.
9. In a brake-shoe fastening, the combination of a brake-head provided with notched upper and lower ends, a brake-shoe provided with a central lug and a lower projection, a key passing through said lug and having an upper hooked terminal engaging the upper notched end of the brake-shoe, and an adjustable clip upon the lower end of the key and engaging the lower notched end of the brake-head, the lower end of the key being arranged to bear upon the said projection.

In testimony whereof I affix my signature in presence of two witnesses.

SAMUEL WEBB.
